UNITED STATES PATENT OFFICE.

FRANKLIN L. LANE, OF BELOIT, WISCONSIN, ASSIGNOR TO P. B. YATES MACHINE COMPANY, OF BELOIT, WISCONSIN, A CORPORATION OF WISCONSIN.

MATCHER-HEAD.

1,213,888.

Specification of Letters Patent. Patented Jan. 30, 1917.

Application filed September 27, 1915. Serial No. 52,818.

To all whom it may concern:

Be it known that I, FRANKLIN L. LANE, a citizen of the United States, residing at Beloit, in the county of Rock and State of Wisconsin, have invented certain new and useful Improvements in Matcher-Heads, of which the following is a specification.

The invention has to do with the provision of an improved form of duplex tool head of the general type shown in Patent 1,036,862, issued to me on August 27, 1912, wherein each component part of the head has tools arranged radially about its periphery, the tools of the respective parts interfitted in such manner as to act in succession on the stock.

The invention also concerns the provision of improved means for clamping the head on the shaft.

20 In order that the invention may be readily understood by those skilled in the art, I have in the accompanying drawings and in the following detailed description predicated thereon set forth a preferred embodiment of the invention. As obviously the invention may be embodied in other varied and constructional forms without departure from the essence thereof or sacrifice of its material advantages, it is to be understood that the description and drawing are to be taken in an illustrative and not in an unnecessarily limiting sense.

In the drawings Figure 1 is a side elevation of a matcher head embodying the invention; Fig. 2 is an end elevation of the same; Fig. 3 is a longitudinal section through Fig. 1; Fig. 4 is a similar section taken upon a different line; and Fig. 5 is a transverse section on the line 5-5 of Fig. 3.

The matcher head illustrated in the drawings is really made up of two head members, one of these indicated at 11, having a tubular hub 12, the bore 13 of which is provided at each end with a beveled approach 14 and 15 respectively. The head 11 has projecting therefrom radial arms 11^a having secured thereon in any suitable manner tools 16. As here illustrated the tools are secured in position by means of clamps 17 having lips 18 engaging over the tool 16 and another lip 19 engaging the beveled surface 20 of the arm of the tool head, the two clamps 17 being drawn together by

means of the nut 21 on the bolt 22 which 55 passes through the arm and into engagement with both of the clamps. The other tool head 23 has likewise a tubular hub 24 but the interior of the hub 24 is cylindrical instead of having beveled approaches as in 60 the other case. The hub 23 has similar radial projections 23^a provided with tools as in the case of the projections 11^a, the arms 23 and their tools lying in the spaces between the arms 11^a and the tools 16 and 65 bearing laterally thereon to prevent angular displacement.

It will be readily understood that the tools 16 carried by the arms of the respective tool heads 11 and 23 act in succession 70 upon the stock. In the drawing these tools are represented as groove forming tools and they are arranged alternately at different slight angles to the plane of rotation. It will thus be seen that each of the tools 75 forms a clearance for the following tool. The cutting edge 16^a (Fig. 1) cuts the bottom and one side of the groove while the succeeding tool 16^b cuts the bottom and the opposite side of the groove. In order to 80 shift the position of the groove or tongue upon the stock or to cut a wider or narrower groove, it is only necessary to shift axially one of the sets of cutting edges 16^a or 16^b with reference to the other set. This 85 is done by shifting that head member which carries the cutting edges 16^a and that head member which carries the cutting edges 16^b a greater or less distance. I provide improved means for adjusting these members 90 axially in the manner following: The hubs 12 and 24 of the heads 11 and 23 respectively are telescopically arranged, the hub 12 snugly fitting within the hub 24. The former extends beyond the end of the latter 95 and the end portions of each are screw threaded as indicated at 25 and 26, respectively, the threads 25 being of coarser pitch than the threads 26. An adjusting nut 27 has a threaded portion 28 in engagement 100 with the thread 25 of the hub 12 and another portion 29 having threads in engagement with the threads 26 of the hub 24. The threaded portion 25 of the hub 12 is provided with a lock nut 30 adapted to bear 105 against the upper end of the adjusting nut 27 and the threads 26 of the hub 24 are likewise engaged by a lock nut 31 adapted to

bear against the opposite end of the adjusting nut 29.

It will be readily understood that the concentric hubs 12 and 24 of the two component head members having been slipped 5 one upon the other in telescopic relation with the projecting arms 11^a and 23^a and their tools interfitted, and the adjusting nut 27 having been brought into position with its threads engaging the threads 25 and 26 10 of the hubs 12 and 24, the rotation of the adjusting nut 27 will, by reason of the different pitch of the threads 25 and 26, cause the hub 23 to move in one direction and the head 11 to move in the same direction 15 but at a different rate of speed, whereby the relative location of the tool heads will be axially adjusted.

In order to provide for the fixed adjusted mounting of the duplex cutter head 20 upon the end of the shaft 32 the following provision is made: About the shaft 32 and within the central bore of the hub 12 is disposed a sleeve 33 which is cup-shaped and has its open end enlarged as indicated at 25 34 and provided with an exterior beveled face 35 adapted to coöperate with the beveled face 14 on the approach to the bore 15 of the hub. The side walls of the sleeve 30 33 are longitudinally slotted to lend resiliency in order that the same may expand and contract, and the closed end of the sleeve which is cup-shaped is provided with a central aperture interiorly threaded as indicated at 36. At the opposite end of the bore 13 is arranged another cup-shaped sleeve 37 the walls of which are longitudinally slotted and exteriorly beveled at their open end as indicated at 38 for coöperation 40 with the beveled approach 15 to said bore.

The closed end of this cup sleeve is likewise provided with an axial aperture 39 interiorly threaded, the threads of the aperture 39 having a different pitch from those of the aperture 36.

The relative axial movement of the sleeves 33 and 37 whereby their beveled ends 38 and 35 are caused to act upon the beveled faces 14 and 15 of the approaches of the bore 13, is effected by means of a duplex screw. This duplex screw comprises a tubular screw member 40 having threaded portions 41 and 42 of different diameter and pitch for engaging within the threaded portions 36 and 39 of the two sleeves, such tubular screw 40 being rotated by means of its polygonal head. The tubular screw 40 is axially bored and interiorly threaded and has seated therein a second screw member 43 provided with a polygonal head 44 and having an inner end 45 projecting beyond the tubular screw 40 into engagement with the end of the shaft 32. Upon the inner screw member 43 is mounted a lock nut 46 65 which is adapted to bear upon the head of

the tubular screw 40. A stud 47 seated within the enlarged end 34 of the sleeve 33 takes into a groove formed in the end of the hub 12 so as to prevent relative rotation of the sleeve and hub. Similarly a stud 48 seated in the bottom of the cup-shaped sleeve 37 takes into an aperture 49 in the bottom of the cup-like sleeve 43 whereby the two sleeves 33 and 37 are locked against relative rotation while permitting freely of 75 longitudinal or axial movement.

The two sleeves having been arranged in telescopic relation within the hub 12 with their beveled faces bearing against the beveled approaches to the bore of the hub 12 and 80 with the bottom portions of the sleeve 33 enveloped by the bottom portion of the sleeve 37, the tubular screw 40 is inserted within the threaded aperture 36 and 39 and, the lock nut 46 having been loosened the screw 43 85 is so adjusted within the tubular screw 40 as to properly position the cutter head upon the shaft 32. This adjustment having been secured the tubular screw 40 is manipulated by means of its head so as to move the sleeve 90 33 in one direction and the sleeve 37 in the opposite direction, thereby causing the beveled faces on the two sleeves to ride upon the beveled approaches of the bore and contract the inner sleeve 33 upon the shaft 32. 95 Thereupon the lock nut 46 is screwed home against the head of the tubular screw 40 and the permanency of the mounting of the head upon the shaft is secured.

I claim:

1. The combination with a tool head having an axial bore with a beveled approach at one end, and a shaft, of means for mounting the head on the shaft comprising a sleeve enlarged at one end with a beveled exterior face for coöperation with the beveled approach of the bore, an abutment for the head at the opposite end of the bore, said abutment enveloping the closed end of the sleeve, a screw passing through the 105 closed end of the abutment and sleeve and engaging the same with right and left hand threads respectively and bearing inwardly on the shaft end, whereby the turning of the screw will shift the abutment and sleeve 110 simultaneously in opposite directions and cause the sleeve to be contracted on the shaft by the beveled coacting surfaces.

2. The combination with a tool head having an axial bore with beveled approaches 120 at both ends, and a shaft, of means for mounting the head on the shaft comprising a sleeve enlarged at its one end with beveled exterior face for coöperation with the beveled approach at one end of the bore, a 125 sleeve abutment for the head at the opposite end of the bore, said abutment having a beveled face for coöperation with the beveled approach at that end of the bore and enveloping the first sleeve, and means to effect 130

relative axial movement of the two sleeves, said means including an element bearing on the shaft end to determine the position of the head relative to the shaft.

5. 3. The combination with a tool head having an axial bore with beveled approaches at both ends, and a shaft, of means for mounting the head on the shaft comprising a cup-shaped sleeve enlarged at its one end 10 with beveled exterior face for coöperation with the beveled approach at one end of the bore, a cup-shaped sleeve abutment for the head at the opposite end of the bore, said abutment having a beveled face for coöperation 15 with the beveled approach at that end of the bore and enveloping the first sleeve, a right and left hand screw engaging the two sleeves and including an element bearing inwardly on the shaft end, whereby the 20 turning of the screw will shift the two sleeves simultaneously in opposite directions and cause the inner sleeve to be contracted on the shaft by the beveled co-acting surfaces.
25. 4. The combination with a tool head having an axial bore with beveled approaches at both ends, and a shaft, of means for mounting the head on the shaft comprising a cup-shaped sleeve enlarged at its one end 30 with beveled exterior face for coöperation with the beveled approach at one end of the bore, a cup-shaped sleeve abutment for the head at the opposite end of the bore, said abutment having a beveled face for coöperation 35 with the beveled approach at that end of the bore and enveloping the closed end of the first sleeve, a screw passing through the closed end of the two cup-shaped sleeves and engaging the same with right and left 40 hand threads respectively and bearing inwardly on the shaft end, whereby the turning of the screw will shift the two sleeves simultaneously in opposite directions and cause the inner sleeve to be contracted on the 45 shaft by the beveled coacting surfaces.
5. The combination with a tool head having an axial bore with beveled approaches at both ends, and a shaft, of means for mounting the head on the shaft comprising 50 a cup-shaped sleeve enlarged at its one end with beveled exterior face for coöperation with the beveled approach at one end of the bore, a cup-shaped sleeve abutment for the head at the opposite end of the bore, said 55 abutment having a beveled face for coöperation with the beveled approach at that end of the bore and enveloping the closed end of the first sleeve, means to lock the two sleeves against relative rotation while permitting 60 of axial displacement, a screw passing through the closed end of the two cup-shaped sleeves and engaging the same with right and left hand threads respectively and bearing inwardly on the shaft end, whereby 65 by the turning of the screw will shift the two sleeves simultaneously in opposite directions and cause the inner sleeve to be contracted on the shaft by the beveled co-acting surfaces.
6. The combination with a tool head having an axial bore with beveled approaches at both ends, and a shaft, of means for mounting the head on the shaft comprising a cup-shaped sleeve enlarged at its one end 70 with beveled exterior face for coöperation with the beveled approach at one end of the bore, a cup-shaped sleeve abutment for the head at the opposite end of the bore, said abutment having a beveled face for coöperation 75 with the beveled approach at that end of the bore and enveloping the closed end of the first sleeve, a screw having exteriorly threaded portions of different diameter and with diverse threads, that of smaller diameter threaded in the end of the inner sleeve 80 and that of larger diameter in the outer sleeve, whereby the turning of the screw will shift the two sleeves simultaneously in opposite directions and cause the inner sleeve to be contracted on the shaft by the beveled 85 coacting surfaces.
7. The combination with a tool head having an axial bore with beveled approaches at both ends, and a shaft, of means for mounting the head on the shaft comprising a cup-shaped sleeve enlarged at its one end 90 with beveled exterior face for coöperation with the beveled approach at one end of the bore, a cup-shaped sleeve abutment for the head at the opposite end of the bore, said abutment having a beveled face for coöperation 95 with the beveled approach at that end of the bore and enveloping the closed end of the first sleeve, a duplex screw comprising a tubular screw member having exteriorly threaded portions of different diameter and with right and left hand threads, that of smaller diameter threaded in the end of the inner sleeve and that of larger diameter in the outer sleeve, said tubular screw 100 member interiorly threaded and having seated therein a second screw member provided with a lock nut and having its end extending into the interior of the inner sleeve and bearing on the end of the shaft, whereby 105 the turning of the screw will shift the two sleeves simultaneously in opposite directions and cause the inner sleeve to be contracted on the shaft by the beveled coacting surfaces.
8. The combination with a tool head having an axial bore with beveled approaches at both ends, and a shaft, of means for mounting the head on the shaft comprising a cup-shaped sleeve enlarged at its one end 110 with beveled exterior face for coöperation with the beveled approach at one end of the bore, a cup-shaped sleeve abutment for the head at the opposite end of the bore, said abutment having a beveled face for coöperation 115 with the beveled approach at that end of the bore and enveloping the closed end of the first sleeve, means to lock the two sleeves against relative rotation while permitting 120 of axial displacement, a screw passing through the closed end of the two cup-shaped sleeves and engaging the same with right and left hand threads respectively and bearing inwardly on the shaft end, whereby 125 by the turning of the screw will shift the two sleeves simultaneously in opposite directions and cause the inner sleeve to be contracted on the shaft by the beveled co-acting surfaces.

ation with the beveled approach at that end of the bore and enveloping the closed end of the first sleeve, means to lock the two sleeves against relative rotation while permitting of axial displacement, a screw passing through the closed end of the two cup-shaped sleeves and engaging the same with diverse threads, whereby the turning of the screw will shift the two sleeves simultaneously in opposite directions and cause

the inner sleeve to be contracted on the shaft by the beveled coating surfaces.

In witness whereof I have hereunto signed my name in the presence of two subscribing witnesses.
